ISAAC B. WHIPPLE, OF GLOVERSVILLE, NEW YORK.

Design No. 4,865, dated May 2, 1871.

DESIGN FOR A RE-ENFORCING THUMB-PIECE OF GLOVES.

The Schedule referred to in these Letters Patent and making part of the same.

To all whom it may concern:

Be it known that I, ISAAC B. WHIPPLE, of Gloversville, in the county of Fulton and State of New York, have invented a new and original Design for a Re-enforcing Thumb-piece of Glove; and I do hereby declare that the following is a full, clear, and exact description thereof, which will enable others skilled in the art to make and use the same, reference being had to the accompanying drawing forming part of this specification.

Figure 1 represents a face view of the re-enforcing thumb-piece, placed upon the regular thumb-piece.

Figure 2 is a perspective view of the glove, provided with the same.

Similar letters of reference indicate corresponding parts.

This invention relates to a new form of re-enforcing thumb-piece for gloves, and consists in making the same with double points and tail-pieces, so that it will leave no seam on the back of the thumb.

A in the drawing represents the thumb-piece of a glove, made substantially of the ordinary form, to constitute, when viewed, both the back and inner side of thumb.

Upon this piece A is placed the re-enforcing piece B, which is forked at both ends to form the double points *a* and the double tails *b*.

This piece, when secured to the thumb-piece in the position shown in fig. 1, will form a single strengthening attachment, as in fig. 2, which has no seam in the middle.

I claim as my invention—

The design for a re-enforcing thumb-piece, as shown.

The above specification of my invention signed by me this 1st day of April, 1871.

ISAAC B. WHIPPLE.
